UNITED STATES PATENT OFFICE

167,960

ANIMAL FIGURE OR THE LIKE

Marianne Tuteur, New York, N. Y.

Application January 17, 1952, Serial No. 18,094

Term of patent 14 years

(Cl. D34—2)

To all whom it may concern:

Be it known that I, Marianne Tuteur, a citizen of the United States, residing at New York, in the county and State of New York, have invented a new, original, and ornamental design for an Animal Figure or the like, of which the following is a specification, reference being had to the accompanying drawing forming a part thereof.

In the drawing:

Fig. 1 is a side perspective view of an animal figure or the like, showing my new design with the outer covering closed;

Fig. 2 is a side perspective view thereof, showing the outer covering in open position; and

Fig. 3 is a perspective view, showing the rear and side of the animal figure or the like, as shown in Fig. 1.

I claim:

The ornamental design for an animal figure or the like, substantially as shown.

MARIANNE TUTEUR.
